UNITED STATES PATENT OFFICE

2,431,561

PHOTO AND MATCH BOOK HOLDER WITH
SECRET POCKET

Sidney Hyman, New York, N. Y.

Application May 27, 1944, Serial No. 537,637

3 Claims. (Cl. 206—33)

1

This invention relates to new and useful means in a photo match pack.

More specifically the invention proposes the construction of a photo match pack constructed of leather, fabric, imitation leather, heavy paper, or other similar materials and arranged in a manner to conveniently carry a book of safety matches and one or more small photographs. The arrangement of the pack is such that the photograph will be exposed to view each time the pack is opened for the purpose of removing one of the matches.

Still further it is proposed to characterize the match pack by an outer cover sheet of flexible material for engaging over the cover of a pack of matches to completely enclose the same when folded in half.

A further object proposes the provision of an inner sheet secured at its sides and top end to the adjacent portions of the outer cover sheet for forming a pocket. This pocket is arranged to receive the top leaf of a conventionally constructed book of matches and is formed with a window opening through which a picture may be viewed when inserted into this pocket in a superimposed position upon said top leaf.

Still another object of the invention proposes the provision of an inner sheet secured to the bottom end of the outer sheet to form a pocket for receiving the bottom end portion of the bottom leaf on a conventionally constructed book of matches. This inner sheet is formed with an opening in an aligned position with that occupied by the match striking pad of the book of matches to permit a match to be scraped thereon to ignite the match, with the book of matches in position in the pack.

Still another form of the invention proposes the provision of a secret pocket sheet mounted on the inner face of the outer cover in a position beneath the cover of the book of matches, and which is arranged in a manner to receive paper money or small other valuable papers.

It is a further object of this invention to construct a photo match pack which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

2

Fig. 1 is a perspective view of a photo match pack which is constructed in accordance with this invention.

Fig. 2 is a perspective view of a photo match pack in its completely open position.

Fig. 3 is a view similar to Fig. 2 but illustrating the match pack with the book of matches completely removed therefrom.

Fig. 4 is a sectional view taken on the line 4—4 of Fig. 3.

Fig. 5 is a sectional view taken on the line 5—5 of Fig. 3.

Fig. 6 is a view similar to Fig. 1 but illustrating a modification of the invention.

Fig. 7 is an elevational view of the photo match pack illustrated in Fig. 6 in its complete open position.

Fig. 8 is a perspective view of the secret pocket sheet per se as used in the form of the invention shown in Fig. 7.

Fig. 9 is a perspective view similar to Fig. 3 but illustrating a further modification of the invention.

A pocket match pack, according to this invention, includes an outer cover sheet 10 of flexible material for engaging over the cover 11 of a conventionally constructed book of matches 12. The cover sheet 10 is preferably constructed of leather, fabric, imitation leather, heavy paper or other similar materials. An inner sheet 13 is secured at its sides and top end to the side and top end portion of the outer cover sheet forming a pocket 14 for a top leaf 15 of the match pocket 11. The inner sheet 13 is in the form of a continuation

extending from the top edge of the cover sheet 10 and is folded into a superimposed position upon the top portion of the cover sheet 10. The sides and top edges of the inner sheet 13 and cover sheet 10 are secured together by lines of 40 stitches 16.

The inner sheet 13 is formed with a window opening 17 and has a sheet of Cellophane 18 extended thereacross. The pocket 14 is adapted

45 to receive a picture 19 positioned upon the top leaf 15 and beneath the Cellophane sheet 18 to be viewed through the window opening 17 and the inner sheet 13.

A second inner sheet 20 is secured at its sides and its bottom end to the sides and bottom end portion of the outer sheet 10 forming a pocket for the bottom end portion of the bottom leaf 21 of the cover 11 of a conventionally constructed packet of matches. This second inner sheet 20 is in the form of a continuation from the bottom 50 edge of the cover sheet 10 and is bent into a super-

3

imposed position upon the cover sheet 10 and is secured in position by lines of stitches 22.

This second inner sheet 20 is formed with an opening 23 through which the scratch portion 24 of the book of matches 12 is exposed for igniting one of the matches when removed from the book.

The photo match pack is adapted to be folded in half along the center line A—B to reduce the compass thereof and permit the folder to be conveniently carried in the pocket of the user. Means is provided for retaining the match pack in this folded position in which the outer cover sheet 19 will completely enclose the book of matches. This is accomplished by means of the flap 25 attached to one portion of the cover sheet by means of a line of stitches 26 and which is provided at its free end with the snap fastener element 27. In folded condition of the match pack as shown in Fig. 1, the snap fastener element 27 is engageable with a complementary snap fastener element 28 mounted on the opposed end of the cover sheet 10.

A secret pocket sheet 29 is mounted on the inner face of the outer cover 10 in a normal position beneath the book of matches. This secret pocket sheet has one end extended into a pocket 14 to the top thereof and is secured in position by means of the line of stitches 16 securely mounting this end in position in the pocket. The outer end of this pocket sheet 29 is adapted to be engaged beneath a lug 30 which extends from the end of the flap 25. This lug 30 is projected into the interior of the cover sheet 10 through a slot 31 formed in the cover sheet 10 adjacent the line of stitches 26 which secures the flap 25 in position upon the cover sheet 10.

The outer end of the secret pocket sheet 29 is adapted to be disengaged from the lug 30 permitting it to be pivoted away from the adjacent face of the cover sheet in the removed position of the pack of matches, as illustrated in Fig. 3, so as to permit paper money or other valuable papers to be inserted between the adjacent faces of the cover sheet 10 and the secret pocket sheet 29. The free end of the pocket sheet 29 may then be re-engaged with the lug 30 to retain the materials in position therein.

In the modification of the invention disclosed in Figs. 6 and 7 the construction of the photo match pack is similar to that previously described except in the formation of an auxiliary pocket 14' extended beyond the top edge of the pocket 14. This pocket is similar in construction to the pocket 14 and cooperates with the pocket 14 to provide two pockets for carrying two pictures. In folding the match pack in this form of the invention the pocket 14' is folded into a superimposed position upon the pocket 14 along the line C—D, and the superimposed pockets are folded into a superimposed position on the bottom portion of the cover sheet 10 along the line E—F. The match pack will then appear as shown in Fig. 6.

The secret pocket sheet 29' in this form of the invention is provided with flaps 32 along the sides and the bottom edge of its outer projected portion. These flaps 32 are adapted to be folded along the lines G and H (see Fig. 8) about the papers inserted beneath the pocket sheet 29' to retain the papers and prevent them from falling out of this pocket. The flaps will then be folded into the position shown in Fig. 7. The free end of the pocket sheet 29' may then be re-engaged with the lug.

In other respects this form of the invention is similar to that previously shown and like reference numerals identify like parts in each of the several views.

5 In the modification of the invention disclosed in Fig. 9 the construction of the photo match pack is similar to that previously disclosed except for the provision of auxiliary pockets 14" extended from the sides of the pocket 14. Each 10 of these pockets 14" is similar in construction to the pocket 14.

The match pack illustrated in Fig. 9 is closed by folding the pockets 14" into a superimposed position upon the pockets 14 along the lines K and L. These superimposed pockets are then folded into the superimposed position upon the bottom portion of the covered sheet 10 along the line I—J.

In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

30 Having thus described my invention, what I claim as new, and desire to secure by United States Letters Patent is:

1. A photo match pack having an outer cover sheet for extending over the cover of a conventional book of matches and provided at the ends of its inner face with pockets for receiving the free ends of the cover of the book of matches when in open position and a book of matches in said cover sheet and having the free ends of said cover disposed in said pockets, and a secret pocket for said outer cover sheet, comprising a strip of material disposed between the adjacent faces of said outer cover sheet and the cover of said book of matches, said strip having one end 35 inserted into and secured in position in one of said pockets, and means releasably securing the free end of said outer cover sheet, comprising a lug mounted on the inner face of said outer cover sheet and having a free portion beneath 40 which the free end of said strip may be inserted.

2. A photo match pack having an outer cover sheet for extending over the cover of a conventional book of matches and provided at the ends of its inner face with pockets for receiving the free ends of the cover of the book of matches when in open position and a book of matches in said cover sheet and having the free ends of said cover disposed in said pockets, and a secret pocket for said outer cover sheet, comprising a strip of material disposed between the adjacent faces of said outer cover sheet and the cover of said book of matches, said strip having one end inserted into and secured in position in one of said pockets, and means releasably securing the free end 45 of said strip to said outer cover sheet, comprising a lug mounted on the inner face of said outer cover sheet and having a free portion beneath which the free end of said strip may be inserted, and flaps on the edges of the free end of said strip adapted to be folded about the edges of articles inserted into said pocket before said free end is engaged with said lug preventing the accidental loss of said article.

3. A photo match pack having an outer cover sheet for extending over the cover of a conven-

tional book of matches and provided at each end of its inner face with a pocket adapted to receive one of the ends of the match book cover when in open position and a book of matches in said cover sheet having the ends of its cover disposed in said pockets, a secret pocket for said outer cover sheet, comprising a strip of material disposed between faces of said outer cover sheet and the cover of said book of matches, said strip having an end inserted into and secured in position in one of said pockets, and means releasably securing a free end of said strip to said outer cover sheet, comprising a lug mounted on the inner face of said outer cover sheet and having means

beneath which the free end of said strip may be inserted.

SIDNEY HYMAN.
